SAFETY DEVICE FOR A BASKET
Lee M. Hoard, San Lorenzo, Calif., assignor to Utility
Body Company, a corporation of California
Filed Dec. 2, 1963, Ser. No. 328,784
10 Claims. (Cl. 182—2)

This is a continuation-in-part of application Serial No. 251,845 filed January 16, 1963, now abandoned.

This invention relates in general to a safety device and more particularly to a safety device for a platform or basket which is pivoted at one side or edge thereof or at a point adjacent the bottom and which may therefore be subject to sudden and undesired pivoting on failure of its control mechanism.

Ladders or booms mounted so that they may be raised or lowered and which support work platforms or baskets for use at elevated locations such as for power line work, tree trimming and the like, are well known. One form utilizes a work platform or basket which is pivoted at the side or base thereof. This arrangement has various advantages which are well understood to those skilled in the art and need not be detailed here. Because the tendency of such platforms or baskets is to pivot under the influence of gravity so that ultimately the base or platform will rest more or less vertically, it is necessary to provide means for maintaining such platforms in a horizontal position. This involves continuously changing the angle between the horizontal platform and the boom upon which it is mounted as the boom is raised or lowered; an hydraulic cylinder assembly pivoted at one end thereof to the boom and at the other end thereof to the platform represents a convenient leveling mechanism. Automatic control means are provided, as is well understood, for retracting the piston rod as the boom is lowered and for extending the piston rod as the boom is raised.

It is obvious that in the event of failure of any of the links between the leveling cylinder assembly and the boom or work platform, or in the event of failure of the associated hydraulic system, the work platform would rotate about its pivot point and pitch the workman, tools, etc. to the ground.

It is an object of this invention to provide a safety apparatus for a work platform or basket generally of the type aforementioned.

It is a further object of this invention to provide a safety device which will prevent a work platform or basket from pivoting freely on loss of power to or failure of the hydraulic cylinder which is relied upon to level the platform.

Other objects and advantages of this invention, if not specifically set forth, will become apparent during the course of the description which follows.

In the drawings:

FIGURE 1 is a schematic fragmentary side elevation of a supporting boom, basket and associated leveling and safety apparatus.

FIGURE 2 is a fragmentary side elevational view showing a boom and basket in different relative positions which omits the schematic representation of the safety features.

FIGURE 3 is a view on the line 3—3 of FIGURE 1 showing the relationship of the various parts.

FIGURE 4 is an enlarged sectional view of the valve which forms a portion of the safety apparatus.

FIGURE 5 is a fragmentary side elevation of another embodiment of the invention wherein the platform is piv-

2

oted to the supporting boom at a point beneath the platform and located intermediate its ends so that the platform is susceptible to tipping in either direction on failure of the control mechanism.

5 FIGURE 6 is a schematic representation of the safety mechanism of FIGURE 5.

Generally, this invention comprises a safety apparatus for a platform hinged at one edge or along the bottom thereof to a boom capable of being angularly raised and lowered. There is provided a first hydraulic cylinder-piston-rod assembly pivoted at one end thereof to the boom and at the other end thereof to the platform. The assembly is pivoted to the platform whereby to provide means for varying the angle between the boom and the platform and for leveling the platform. There is also provided means for preventing a sudden change in the angle between the boom and platform on failure of the first hydraulic cylinder-piston-rod assembly. This means consists of a second hydraulic cylinder assembly secured at one end thereof to the boom and at the other end thereof to the platform, the second cylinder assembly just mentioned being pivoted to the boom or platform at a point spaced from the point at which the platform itself is hinged to the boom. There is also provided an 15 hydraulic fluid line connecting the piston side of the cylinder of the second assembly aforementioned and the rod side of the cylinder of the assembly aforementioned or, more generally expressed, joining the two ends of the cylinder on either side of the piston. In this line is a counterbalance valve. A counterbalance valve may be defined as an adjustable relief valve and a free-flow check valve assembled together in one body in such a way as to allow essentially free flow through the valve in one direction and a relief valve action when the flow is in the other direction. The counterbalance valve is set to prevent 20 flow of fluid and therefore tipping of the basket except when there is a positive force applied to the basket which would create a pressure within the safety cylinder sufficient to overbalance the setting of the counterbalance valve. The source of this positive force is the first or leveling cylinder assembly. If there is a failure of any kind in the leveling cylinder or of the hydraulic circuit of the leveling cylinder itself, there would be no positive force available to overbalance the counterbalance valve; 25 therefore, the basket would remain in the position at which failure of the valve or its hydraulic system occurred.

Referring now to the drawings wherein like characters refer to like parts throughout, there is shown in FIGURES 1—4 a boom 10 which may or may not be extensible, as desired. Pivoted at 12 is the basket 14 which includes platform portion 16 and side walls 18. The basket is conventionally made of Fiberglas. The first or leveling hydraulic cylinder-piston-rod assembly 20 is pivoted at one end thereof at point 22 to boss 24 secured to boom 10 and at the other end thereof at point 26 to boss 28, in turn secured to a point on one wall of the basket, which point is vertically displaced from pivot 12. The second or safety hydraulic cylinder-piston-rod assembly 30 is pivoted at 32 to the distal end of the boom 10 and pivoted at point 34 to the boss 35 which is vertically spaced on basket 14 from pivot 12.

The assembly 30 has oil on either side of the piston and means are provided for transferring oil from the cylinder side of the piston to the rod side or vice versa. The means consist of fluid line 36 having therein the relief

valve 38 which is shown schematically in FIGURE 1 and in cross section in FIGURE 4. In communication with the fluid line 36 by means of line 40 is the reservoir 42 which serves to provide fluid for the piston side of the safety cylinder in excess of the fluid forced from the rod side of the safety cylinder at such time as the piston is moved to extend the piston rod. Obviously, because of the volume represented by the rod of the assembly 30, movement of the piston thereof downwardly would create a greater requirement for hydraulic fluid on the piston side than can be satisfied by the fluid forced from the rod side through line 36. The reservoir 42 supplies the necessary extra fluid. The interior of the reservoir is conveniently at about one atmosphere pressure when supplying oil to the piston side of safety cylinder assembly 30 as shown in FIGURE 1 and at about two atmospheres pressure when serving as a reservoir for a maximum quantity of oil and when the condition represented in FIGURE 2 obtains.

A typical valve incorporating a relief valve and a check valve and generally designated a counterbalance valve is shown in section in FIGURE 4. The valve housing 50 has inlet port 52 and return port 54, the former being connected to the piston side of piston assembly 30 via line 36. Compression spring 56 is held in place by means of cylindrical counterbored plug 58. O-ring 60 assures a tight seal against fluid leaks. The spring 56 bears against ball 62 which is seated at the mouth of passage 64. The spring is suitably sized so that ball 62 will move against the spring tension on application of a low pressure, e.g. one p.s.i. This provides for the return of fluid from the piston side of the cylinder assembly 30 to the rod side when the boom 10 is being lowered, and the platform or basket is pivoting upwardly relative thereto. On the application of any positive pressure from the direction of port 54, the ball tends to seat more securely. Movement of fluid through passages 66 and 68 is normally blocked by cylindrical hollow sleeve 70 which is slidably mounted therein and provided with suitable sealing rings 72 and 74. As the boom 10 is elevated, fluid must be removed from the rod side of the cylinder assembly 30 and passed to the piston side. Spring 76 is held in place by plug 78 covered by cap 77 and exerts a pressure on the hollow sleeve 70 so as to obstruct the passage of fluid from the rod side of safety assembly 30. Pressure in excess of the spring setting applied through passage 66 forces the sleeve toward the bottom in FIGURE 4 whereby to open the entire route for hydraulic fluid extending from return port 54 through passage 66, passage 68 and out inlet port 52 to the piston side of assembly 30.

An alternative double-acting safety apparatus is shown in FIGURES 5 and 6 wherein a boom 100 has a sprocket 102 keyed thereto. Pivoted about point 103 at the center of the sprocket is the generally V-shaped framework 104 which supports the horizontal platform frame member 106, in turn supporting side railing assembly 108. As in the case of structures 1-4, a leveling cylinder 110 is supported by the boom. Specifically, the cylinder 110 with its piston rod 112 is pivoted at one end thereof to the parallel ears 114 which are in a fixed orientation relative to the boom. The piston rod 112 is pivoted to the under side of the platform at point 116. A pair of idler sprockets 118 and 120 serve, with fixed sprocket 102, to provide a complete support for the link chain 122. Ends of the chain are secured respectively to piston rods 124 and 126, in turn secured on opposite sides of piston 128 which slides in cylinder 130. A system somewhat similar to that of the structure of FIGURES 1-4 provides the safety feature, including, as shown in the schematic view of FIGURE 6, a pair of relief valves, respectively 132 and 134, and a pair of check valves 136 and 138, together with a reservoir or accumulator 140. Each valve assembly consists of a relief valve 132 or 134 with its respective parallel-mounted check valve 136 or 138 and can be provided in the form of the valve of FIGURE 4, thus providing two of these valves together with an intermediate reservoir.

The volumes on either side of piston 128 are filled with hydraulic fluid and the lines 142 and 144 permit flow of such fluid from one side of the cylinder to the other, such flow, in one direction, always being through a single combination of a relief valve and a check valve in series therewith, e.g. through valves 132 and 138 when the fluid flows from the left side to the right, as seen in FIGURE 6.

In the operation of the structure of FIGURES 1-4, as the boom 10 is raised, the rod of the safety cylinder 30 is extended. The cylinder assembly 20 exerts a pressure in excess of that of spring 76 and fluid moves from the rod side of assembly 30 through passage 66, past the retracted sleeve 70, and through port 52 and line 36, thence to the piston side of the cylinder assembly 30. Additional oil is always provided from reservoir 42. As the boom 10 is lowered, the safety cylinder retracts and oil on the piston side of the cylinder 30 flows readily through the valve after unseating ball 62. In the event of a failure of the leveling cylinder 20, of one of the bosses 24 or 28, or of either of the pins 22 or 26, sleeve 70 will not be retracted and the valve 38 will retain the oil in the rod side of the safety cylinder assembly 30. This prevents further extension of the rod thereof, holding the basket in the position in which it was at the time of the aforementioned failure. With a spring 76 suitably sized to require a pressure of 700 p.s.i. to retract sleeve 70, and with an average load creating a pressure of 450 pounds, it will be possible for the basket to be slowly tipped by the operator jumping up and down to overcome the setting. Otherwise, the basket will be retained in the orientation where the failure occurred.

In the operation of the structures of FIGURES 5 and 6, as the boom is raised, the piston of the safety cylinder 130 moves to the left, given the relationship of the viewer and the platform presented by FIGURES 5 and 6. That is, since sprocket 102 is keyed to the end of the boom and thus moves counter-clockwise with respect to the work platform 106, the chain 122 is moved in a counter-clockwise direction, thereby pulling the piston 128 to the left and forcing hydraulic fluid out of the left side of the cylinder 130. The setting of the relief valve 132, in a preferred embodiment, is at 1800 p.s.i., so that a 2000 lb. or lesser weight offset somewhat from the center of the platform 106 would be insufficient to cause tilting of the platform should the control cylinder 110 or associated hydraulic equipment fail. In the event of failure of any part of the control system aforementioned, the platform would tend to rotate about pivot point 103. Assuming that the platform is unweighted in the direction to cause it to rotate clockwise, chain 122 will pull piston 128 to the left relative to the platform. Sprocket 102 is fixed and this sprocket in turn fixes the chain. Since, as seen in FIGURE 6, the only route by which hydraulic fluid may be expelled from the left side of cylinder 30 is through relief valve 132, clockwise rotation of the entire platform is impossible unless sufficient force is applied to overcome the setting of the valve, as by the larger hydraulic system including cylinder 110.

In the event that the weight tending to cause rotation of the platform at the time of failure of the main control cylinder 110 is at the left of the center of the platform, as seen in FIGURE 5, piston 128 will be pulled to the right by chain 122. This necessitates that the fluid pass through the relief valve 134 following which time it readily passes through the check valve 136. As the fluid passes through the valve 136, a ball similar to that labeled 62 in FIGURE 4 is unseated while, as fluid passes through the relief valve 134, a sleeve similar to sleeve 70 of FIGURE 4 is retracted against the pressure exerted by a spring corresponding to spring 76. Thus, assuming that the platform is not overloaded and such load positioned dangerously close to one edge, failure of the control cylinder 110 or associated system will not result in anything other than the platform retaining its orientation at the time when the failure occurs.

Obviously, many modifications and variations may be made without departing from the spirit and scope of this invention, and therefore only such limitations should be imposed as are indicated in the appended claims.

I claim:

1. A safety apparatus for platform hinged at one end thereof to a boom capable of being angularly raised and lowered from a support therefor comprising:

(a) a first hydraulic cylinder-piston-piston rod assembly pivoted at one end thereof to said boom and at the other end thereof to said platform, said assembly being pivoted to said platform at a point normally vertically displaced from the point at which said platform is hinged to said boom whereby to provide means for varying the angle between said boom and said platform and for maintaining said platform in a horizontal orientation;

(b) means for preventing sudden change in the angle described by said boom and said platform on failure of said first hydraulic cylinder-piston-piston rod assembly, said means comprising a second hydraulic cylinder-piston-piston rod assembly pivoted at one end thereof to said boom and at the other end thereof to said platform, said assembly being pivoted to said platform at a point normally vertically displaced from the point at which the said platform is hinged to said boom;

(c) an hydraulic fluid line connecting the piston side of the cylinder of said second assembly and the rod side of the cylinder of said assembly;

(d) and a valve in the said line, said valve being set to prevent the flow of hydraulic fluid from the one side of said second assembly to another side of said second assembly except on application of pressure in excess of that represented by the weight of the said platform and its normal load when said platform is in use.

2. A safety apparatus for a platform having four walls extending upwardly therefrom to form a basket pivoted at one side thereof to a boom capable of being angularly raised and lowered from a support therefor comprising:

(a) a first hydraulic cylinder-piston-piston rod assembly pivoted at one end thereof to said boom and at the other end thereof to a wall of said platform, said assembly being pivoted to said wall at a point vertically displaced from the point at which said platform is hinged to said boom whereby to provide means for varying the angle between said boom and said platform and for maintaining said platform in a horizontal orientation;

(b) means for preventing a sudden change in the angle described by said boom and said platform on failure of said first hydraulic cylinder-piston-piston rod assembly, said means comprising a second hydraulic cylinder-piston-piston rod assembly pivoted at one end thereof to said boom and at the other end thereof to the said wall whereon the said first assembly is pivoted, said second assembly being pivoted at a point vertically displaced from the point at which the said basket is pivoted to the said boom;

(c) an hydraulic fluid line connecting the piston side of the cylinder of said second assembly and the rod side of the cylinder of said assembly;

(d) and a valve in the said line, said valve being set to prevent the flow of hydraulic fluid from one side of said second assembly to the other side of said second assembly except on application of pressure in excess of that represented by the weight of the said basket and its normal load when said basket is in use.

3. A safety apparatus for a platform having four walls extending upwardly therefrom to form a basket pivoted at one side thereof to a boom capable of being angularly raised and lowered from a support therefor comprising:

(a) a first hydraulic cylinder-piston-piston rod assem-

bly pivoted at one end thereof to said boom and at the other end thereof to a wall of said platform, said assembly being pivoted to said wall at a point normally above the point at which said platform is hinged to said boom whereby to provide means for varying the angle between said boom and said platform and for maintaining said platform in a horizontal orientation;

(b) means for preventing a sudden change in the angle described by the said boom and said platform on failure of said first hydraulic cylinder-piston-piston rod assembly, said means comprising a second hydraulic cylinder-piston-piston rod assembly pivoted at one end thereof to said boom and at the other end thereof to the said wall of the said platform whereat the said first assembly is pivoted, said second assembly being pivoted to said wall at a point normally above the point at which the said first assembly is pivoted to the said boom;

(c) an hydraulic fluid line connecting the piston side of the cylinder of said second assembly and the rod side of the cylinder of said assembly;

(d) and a valve in the said line, said valve being set to prevent the flow of hydraulic fluid from the one side of said second assembly to the other side of said second assembly except on application of pressure in excess of that represented by the weight of the said basket and its normal load when said basket is in use.

4. A safety apparatus for a platform having four walls extending upwardly therefrom to form a basket pivoted at one side thereof to a boom capable of being angularly raised and lowered from a support therefor comprising:

(a) a first hydraulic cylinder-piston-piston rod assembly pivoted at one end thereof to said boom and at the other end thereof to a wall of said platform, said assembly being pivoted to said wall at a point vertically displaced from the point at which said platform is hinged to said boom whereby to provide means for varying the angle between said boom and said platform and for maintaining said platform in a horizontal orientation;

(b) means for preventing a sudden change in the angle described by said boom and said platform on failure of said first hydraulic cylinder-piston-piston rod assembly, said means comprising a second hydraulic cylinder-piston-piston rod assembly pivoted at one end thereof to said boom and at the other end to the said wall whereon the said first assembly is pivoted, said second assembly being pivoted at a point vertically displaced from the point at which the said basket is pivoted to the said boom;

(c) an hydraulic fluid line connecting the piston side of the cylinder of said second assembly and the rod side of the cylinder of said assembly;

(d) a valve in said line, said valve being set to prevent the flow of hydraulic fluid from one side of said second assembly to the other side of said second assembly except on application of pressure in excess of that represented by the weight of the said basket and its normal load when said basket is in use;

(e) and a reservoir for hydraulic fluid in communication with the said line, the interior of said reservoir being under a superatmospheric pressure when the said reservoir is filled to a maximum extent and being under a pressure no less than atmospheric when the said boom is elevated to a maximum extent and the rod of the said second assembly extended to a maximum extent.

5. A safety apparatus for a platform hinged at one end thereof to a boom capable of being angularly raised and lowered from a support therefor comprising:

(a) means for varying the angle between said boom and said platform and for maintaining said platform in a horizontal orientation;

(b) means for preventing a sudden change in the angle

described by said boom and said platform on failure of said first means, said means comprising an hydraulic cylinder-piston-piston rod assembly pivoted at one end to said boom and at the other end thereof to said platform, said assembly being pivoted to said platform at a point normally vertically displaced from the point at which the said platform is hinged to said boom;

- (c) an hydraulic fluid line connecting the piston side of the cylinder of said assembly and the rod side of the cylinder of said assembly;
- (d) and a valve in the said line, said valve being set to prevent the flow of hydraulic fluid from the one side of said assembly to another side of said assembly except on application of pressure in excess of that represented by the weight of the said platform and its normal load when said platform is in use.

6. Safety apparatus for a platform hinged to a boom and capable of being angularly raised and lowered from a support therefor comprising:

- (a) means for varying the angle between said boom and said platform and for maintaining the said platform in a horizontal orientation;
- (b) means for preventing a sudden change in the angle described by said boom and said platform on failure of said first means, said means comprising an hydraulic cylinder-piston-piston rod assembly having means connecting the said assembly to the said platform and to the said boom;
- (c) an hydraulic fluid line connecting one side of the piston of the cylinder of said assembly and the other side of the piston of the cylinder of said assembly;
- (d) and a valve in the said line, said valve being set to prevent the flow of hydraulic fluid from the one side of said assembly to the other side of said assembly except on application of pressure in excess of that represented by the rotational moment of the said platform and its maximum normal load when said platform is in use.

7. Safety apparatus for a platform hinged beneath the bottom thereof to a boom, said boom being capable of being angularly raised and lowered from a support therefor comprising:

- (a) means for varying the angle between said boom and the said platform and for maintaining the said platform in a horizontal orientation;
- (b) means for preventing a sudden change in the angle described by said boom and said platform on failure of said first means, said means comprising an hydraulic cylinder-piston-piston rod assembly, said assembly including a cylinder fixedly secured to the said platform and having a piston fitted with a rod on either side thereof, a sprocket fixed against rotary motion relative to the said boom on the end of said boom supporting said platform and a chain connecting each piston rod and trained about the said sprocket;
- (c) an hydraulic fluid line connecting either side of the said cylinder on either side of the said piston thereof;
- (d) and a valve in the said line, said valve being set to prevent the flow of hydraulic fluid from the one side of said assembly to another side of said assembly except on application of pressure in excess of that represented by the rotational moment of the said platform and its maximum normal load when said platform is in use.

8. Safety apparatus for a platform hinged beneath the bottom thereof to a boom, said boom being capable of being angularly raised and lowered from a support therefor comprising:

- (a) means for varying the angle between said boom and the said platform and for maintaining the said platform in a horizontal orientation;
- (b) means for preventing a sudden change in the angle

described by said boom and said platform on failure of said first means, said means comprising an hydraulic cylinder-piston-piston rod assembly, said assembly including a cylinder fixedly secured to the said platform and having a piston fitted with a rod on either side thereof, a sprocket fixed against rotary motion relative to the said boom on the end of said boom supporting said platform and a chain connecting each piston rod and trained about the said sprocket;

- (c) an hydraulic fluid line connecting either side of the said cylinder on either side of the said piston thereof;

- (d) a valve in the said line, said valve being set to prevent the flow of hydraulic fluid from the one side of said assembly to another side of said assembly except on application of pressure in excess of that represented by the rotational moment of the said platform and its maximum normal load when said platform is in use;

- (e) and an idler sprocket mounted for rotation upon the said platform opposite the end of each of the said piston rods, said chain being trained about said idler sprockets.

9. Safety apparatus for a platform hinged beneath the bottom thereof to a boom, said boom being capable of being angularly raised and lowered from a support therefor comprising:

- (a) means for varying the angle between said boom and the said platform and for maintaining the said platform in a horizontal orientation;
- (b) means for preventing a sudden change in the angle described by said boom and said platform on failure of said first means, said means comprising an hydraulic cylinder-piston-piston rod assembly, said assembly including a cylinder fixedly secured to the said platform and having a piston fitted with a rod on either side thereof, a sprocket fixed against rotary motion relative to the said boom on the end of said boom supporting said platform and a chain connecting each piston rod and trained about the said sprocket;

- (c) an hydraulic fluid line connecting either side of the said cylinder on either side of the said piston thereof;

- (d) and a pair of relief valves in the said line, each of said valves being positioned to permit the flow of hydraulic fluid in one direction only from one side of the said assembly to the other side of the said assembly and preventing flow of fluid except on application of pressure in excess of that represented by the rotational moment of the said platform and its maximum normal load when said platform is in use, each of the said relief valves being provided with a series-mounted check valve, each of said check valves permitting flow of fluid only in the direction opposite to the direction of fluid flow permitted by the corresponding relief valve.

10. Safety apparatus for a platform hinged beneath the bottom thereof to a boom, said boom being capable of being angularly raised and lowered from a support therefor comprising:

- (a) a first hydraulic cylinder-piston-piston rod assembly pivoted at one end thereof to the said boom and at the other end thereof to said platform, whereby to provide means for varying the angle between said boom and said platform and for maintaining said platform in a horizontal orientation;

- (b) means for preventing a sudden change in the angle described by said boom and said platform on failure of said first means, said means comprising a second hydraulic cylinder-piston-piston rod assembly, said assembly including a cylinder fixedly secured to the said platform and having a piston fitted with a rod on either side thereof, a sprocket fixed against rotary motion relative to the said boom on the end of said

boom supporting said platform and a chain connecting each piston rod and trained about the said sprocket;

(c) an hydraulic fluid line connecting either side of the last-mentioned cylinder on either side of the said piston thereof;

(d) and a valve in the said line, said valve being set to prevent the flow of hydraulic fluid from the one side of said last-mentioned assembly to another side of said assembly except on application of pressure in excess of that represented by the rotational

moment of the said platform and its maximum normal load when said platform is in use.
